(57) **CLAIM**

The ornamental design for a fishing transducer cover as shown and described.

DESCRIPTION

FIG. 1 is a top front side perspective view of a fishing transducer cover showing my new design;

FIG. 2 is a bottom rear side perspective view of the fishing transducer cover;

FIG. 3 is a front view of the fishing transducer cover;

FIG. 4 is a rear view of the fishing transducer cover;

FIG. 5 is a left side view of the fishing transducer cover;

FIG. 6 is a right side view of the fishing transducer cover;

FIG. 7 is a top view of the fishing transducer cover;

FIG. 8 is a bottom view of the fishing transducer cover; and,

FIG. 9 is a front view of the fishing transducer cover in an alternative closed condition.

The broken lines on the hems are illustrative of stitching forming no part of the claimed design. The crenate broken lines on the body of the cover are illustrative of stitching forming no part of the claimed design. The broken lines centered on the front face are illustrative of portions of the cover forming no part of the claimed design.

1 Claim, 7 Drawing Sheets
